CLAIM

The ornamental design for a mechanical activator for electrical contactor in a fire pump controller, as shown and described.

DESCRIPTION

FIG. 1 is a left perspective view of a mechanical activator for electrical contactor in a fire pump controller, showing my new design;

FIG. 2 is a front view of the mechanical activator removed from the fire pump controller for ease of illustration;

FIG. 3 is a back view thereof;

FIG. 4 is a top plan view thereof;

FIG. 5 is a bottom view thereof;

FIG. 6 is a right side view thereof;

FIG. 7 is a left side view thereof; and,

FIG. 8 is a right perspective view thereof.

The broken lines in the figures show portions of the mechanical activator for electrical contactor in a fire pump controller that form no part of the claimed design.
